UNITED STATES PATENT OFFICE.

GEORGE S. HENSEL, OF PHILADELPHIA, PENNSYLVANIA, ASSIGNOR TO
HENSEL COLLADAY COMPANY, A CORPORATION OF PENNSYLVANIA.

DESIGN FOR DRESS-TRIMMING.

SPECIFICATION forming part of Design No. 35,913, dated May 13, 1902.

Application filed April 19, 1902. Serial No. 103,802. Term of patent 14 years.

To all whom it may concern:

Be it known that I, GEORGE S. HENSEL, a citizen of the United States, residing in the city and county of Philadelphia, State of Pennsylvania, have invented and produced a new and original Design for Dress-Trimming, of which the following is a specification, reference being had to the accompanying drawings, forming part thereof.

10 The leading feature of my design for a dress-trimming of the order of a skirt-protector is a trimming composed of a head, a brush on the bottom of said head, and a border of scallops on the top thereof.

15 Figure 1 represents a side elevation of a piece of dress-trimming embodying my design. Fig. 2 represents an end view thereof.

In the drawings, A designates a dress-trimming consisting of the head B, the brush C, pendent from the lower edge of said head, and the border D, rising from the upper edge thereof, said border being of the form of scallops, which extend in the longitudinal direction of the head.

Having described my invention, what I claim as new, and desire to secure by Letters Patent, is—

The design for a dress-trimming substantially as shown and described.

GEORGE S. HENSEL.
